SEPARABLE KNIFE-TYPE CLASP CONNECTOR

Irving Frederick Matthyssse, New York, N. Y., assignor to Burndy Engineering Company, Inc., a corporation of New York

Application January 23, 1951, Serial No. 207,348

7 Claims. (Cl. 173—363)

1

This invention relates to improvements in clasp connectors of the separable type in which two separate sections are interlocked together and pivotally or longitudinally moved to release the sections to permit separation of the two halves.

The application is a continuation-in-part of my patent application for Separable Clasp Connectors filed March 31, 1944, Serial No. 528,991.

The principal object of my invention is to provide means to prevent separation of the two connector halves by one half accidentally moving on the other.

Additional objects are to provide a separable connector designed to lock the two halves of the connector together upon the application of a longitudinal pull; to provide a separable connector with a lock which permits disconnection of the two halves only after the halves are pushed together a predetermined distance; to provide a separable connector having a lock which has the added function of providing additional electrical contact when the two halves are pulled longitudinally; to provide a separable connector having resilient contacting means locking the halves together and requiring a predetermined force to separate the two halves by rotating one half with respect to the other; to provide a connector half with means for accommodating the locking means of the other connector half; to provide a separable terminal for connecting a separable connector half to a flat surface; to provide a connector having two identical halves which resiliently engage each other when interengaged; to provide a connector half which is slotted in the plane of the blade to permit a resilient movement of the clip when the counterpart blade is inserted therebetween; and to provide a separable connector of the foregoing type which may be made economically by simple production methods from tubing or sheet metal.

I accomplish these and other objects and obtain my new results as will be apparent from the device described in the following specification, particularly pointed out in the claims, and illustrated in the accompanying drawing, in which:

Fig. 1 is a plan view partially in section of a connector half.

Fig. 2 is a side elevation thereof.

Fig. 3 is a plan view of two pivoting halves.

Fig. 4 is a side view illustrating the interlocking action.

Fig. 5 is a similar view with the two halves pulled into final locking position.

Fig. 6 is a side elevation view of a modified form of a connector half.

2

Figs. 7 and 8 are end and plan views of the same.

Fig. 9 is a plan view of a connection formed by interlocking two counterpart connector halves illustrated in Fig. 8.

Figure 10 is a plan view of a modified connector half.

In the drawing, reference numeral 10 designates a tubular connector body or ferrule for insertion of a conductor 11 therein which is indented as at 12 to lock the conductor to the connector body. A shroud 13 may be additionally provided for the insulation 14 of the conductor upon which the shroud is compressed.

The tubular body is formed with an extending tongue or blade 15, provided with a transversely overhanging spring contact or clip 16. The end of the tongue terminates in a locking tab or limit means 17 normally extending from the edge of the tongue. At the junction of the tongue 15 and body 10, a groove or recess 18 is formed to permit passage of the tab of the complementary half of the separable connector. The slot 19 at the end of the tongue 15 provides means for giving the tab 17 a spring effect as it slides in groove 18a of a complementary or counterpart half. The function of the slot thus is to permit a resilient movement between the spring contact 16 and the tab 17 as the counterpart tongue is inserted therebetween.

Along one edge of the tongue 15, adjacent the groove, a hump or small cam surface 19 is formed which engages the tab of a complementary half as the two connector body halves are locked. This takes place by taking an identical body half 19a, the remaining parts of 19a being similarly identified, and placing the tongue 15a across the flat of tongue 15 of connector body 10, with the two spring contacts on opposite sides, and pivoting the two halves together scissor-like, until tab 17a passes through groove 18 and tab 17 passes through groove 18a. This is shown in Fig. 3. When the tabs pass beyond their engaging grooves, their springy action causes them to snap from the surface of the irrespective grooves to a point 20 beyond the edges, as indicated in Fig. 5. This prevents the tabs from being accidentally forced back into their grooves. During this movement tongue 15 enters the space between tongue 15a and contact spring 16a, and tongue 15a enters the space between tongue 15 and spring contact 16, against the spring of the contacts. The contacts or clips may thus be spaced from their tongues or blades a distance less than the thickness of the counterpart blades.

The locking action is further accomplished by

pulling the two halves longitudinally until the edges of the spring contacts engage, as shown in Fig. 5. During this movement, tab 17a scrapes over cam 19, and tab 17 over cam 19a, which insures a good electrical connection. To separate the two body halves the different operations are reversed.

By the foregoing I have accomplished a satisfactory lock of the two connector halves which will prevent their accidental separation.

The spring lock action of the tab may be eliminated, together with the cam surface 19, and yet retain ample electrical contact and satisfactory locking action.

In Figs. 6 to 9, I have illustrated a device similar to that shown in Fig. 1, in that a clip and a limit means are similarly positioned on opposite sides of the end of the blade, which may be identical in shape. That part of the connector which is positioned between the clips and the ferrule or attaching portion may be recessed or restricted in width to permit the two connector halves to be positioned one over the other, the ends of the clips being sufficiently spaced to allow the clips to enter the recesses whereby a direct longitudinal pull will lock the blades against movement when the blades have been positioned in face-to-face contact.

Specifically each connector half comprises a ferrule or conductor attaching portion 24, the flat tongue or blade 25, the clips 26, the ends 27 of which overhang the blade.

As shown in Fig. 9 the inner surfaces 28 of the clips 26 engage the tapered edges corresponding to 29 of the counterpart blade. Instead of tapered edges, a cam like that of 19 of the device in Fig. 1 may be used to establish contact and prevent removal of the parts. Where tapered edges are employed, the counterpart connector will frictionally lock on the taper, but where a cam is employed, the counterpart connectors may be pulled until the cams prevent further movement.

Between the tapered edges 29 and the ferrule 24, the blade is narrowed or recessed as at 30. The restricted neck portion 31 is of less width than the distance 32 between the edges of the clip. The two counterpart connector halves may be positioned one over the other with the blades adapted to be in face-to-face contact with the overhanging clips of one blade and pulled together until the parts engage. The clips are shaped to permit a smooth engagement and the gradual tapers where used permit a good frictional lock.

Where cams like 19 are employed, the tapered engagement is unnecessary and the clip may be arranged in parallel formation with the sides of the blades as in Fig. 1. Such a device is shown in Fig. 10, where reference numeral 10b designates a tubular connection body provided with a shroud 13b, blade 15b having a neck 18b, clip 16b, limit means 17b, and cam 19b formed on the edge of blade 15b adjacent to the limit means. The two counterpart halves are connected like the devices in Fig. 9. The space between clip 16b and limit means 17b permits insertion over neck 18b, pulled until cam 19b engages the inside surface of limit means 17b.

The principal electrical contact will be at the points of engagement of taper and clip, or at the cam where used. The clips may also be spaced from the blade a distance less than the thickness of the counterpart blade, which will

force the two blades into face-to-face contact, as is illustrated in Figs. 4 and 5.

The metal of the connectors is sufficiently malleable to permit the indentation shown in Fig. 2. Such a material is illustrated in Patent No. 2,287,761 issued to me on June 23, 1942, which similarly discloses indentable material for electrical connectors.

I have thus described my invention, but I desire it understood that it is not confined to the particular form or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

I claim:

1. A separable connector which comprises an attaching portion adapted to be permanently attached to one of the parts which are to be connected by it and a counterpart connector, a blade portion at least a plane contact face of which is adapted to lie in face-to-face contact with a plane face of the blade of a counterpart connector when the connectors are interengaged, and a clip member extending from at least one edge of the blade portion across a portion of said contact face and spaced from it when free a distance less than the thickness of the counterpart blade, whereby to press the counterpart blade and blade portion in said face-to-face contact when interengaged and limit means upwardly from the opposite lateral edge of said blade portion above the level of said contact face to engage a lateral edge of said counterpart blade to limit relative sidewise displacement of the blade portion and counterpart blade when interengaged while permitting relative longitudinal displacement, and a part of the blade portion between said attaching portion and the portion comprising a clip and the limit means being recessed to allow entry of the blade between the clip and limit means and under the clip of a counterpart connector.

2. A separable connector which comprises an attaching portion adapted to be attached to one of the parts which are to be connected by it and a counterpart connector, a body section at least a contact face of which is adapted to lie in face-to-face contact with a contact face of the body section of a counterpart connector when the connectors are interengaged, and a clip member extending from one side of the body section across a portion of said contact face to hold the counterpart body section and contact face into said face-to-face contact when interengaged, and limit means extending from the opposite side of said body section, and above said contact face to engage a portion of said counterpart body section to limit relative displacement of the body section and the counterpart body section in one direction, when interengaged while permitting relative displacement in another direction, and a part of the surface of the body section between said attaching portion and the portion comprising a clip and the limit means being shaped to allow entry of the body section between the clip and the limit

means and under the clip of a counterpart connector.

3. A separable connector which comprises an attaching portion adapted to be attached to one of the parts which are to be connected by it and a counterpart connector, a body section at least a contact face of which is adapted to lie in face-to-face contact with a contact face of the body section of a counterpart connector when the connectors are interengaged, and a clip member extending from one side of the body section across a portion of said contact face to hold the counterpart body section and contact face into said face-to-face contact when interengaged, and limit means extending from the opposite side of said body section, and above said contact face to engage a portion of said counterpart body section to limit relative displacement of the body section and the counterpart body section in one direction, when interengaged while permitting relative displacement in another direction, and a part of the surface of the body section between said attaching portion and the portion comprising a clip and the limit means being shaped to allow entry of the body section between the clip and the limit means under the clip of a counterpart connector, said body section provided with a camming portion over which a portion of the counterpart connector is passed during the interengaging movement thereof to resist accidental disengagement and to obtain a pressure contact between counterpart connectors.

4. A separable connector which comprises an attaching portion adapted to be attached to one of the parts which are to be connected by it and a counterpart connector, a body section at least a contact face of which is adapted to lie in face-to-face contact with a contact face of the body section of a counterpart connector when the connectors are interengaged and a clip member extending from one side of the body section across a portion of said contact face to hold the counterpart body section and contact face into said face-to-face contact when interengaged, and limit means extending from the opposite side of said body section, and above said contact face to engage a portion of said counterpart body section to limit relative displacement of the body section and the counterpart body section in one direction, when interengaged while permitting relative displacement in another direction, and a part of the surface of the body section between said attaching portion and the portion comprising a clip and the limit means being provided with a passageway to allow entry of the body section between the clip and the limit means, and under the clip of a counterpart connector.

5. A pair of separably interengaged and counterpart connectors each of which comprises an attaching portion adapted to be attached to one of the parts which are to be connected by it and its counterpart connector, a blade portion at least a plane contact face of which lies in face-to-face contact with a plane face of the blade of the counterpart connector while the

connectors are interengaged, a clip member extending from at least one edge of the blade portion across a portion of said contact face to hold the interengaged counterpart blade and said blade portion in face-to-face contact, limit means upstanding from the opposite lateral edge of said blade portion above the level of said contact face to engage a lateral edge of said counterpart blade to limit relative sidewise displacement of the blade portion and counterpart blade while permitting relative longitudinal displacement and a low hump formed on said blade portion adapted to hold said connector and said counterpart connector against accidental disengagement, said hump being formed to a height less than would cause an inelastic deformation of the connector upon engagement or disengagement.

6. A separable connector which comprises an attaching portion adapted to be permanently attached to one of the parts which are to be connected by it and a counterpart connector, a blade portion at least a plane contact face of which is adapted to lie in face-to-face contact with a plane face of the blade of a counterpart connector when the connectors are interengaged, and a clip member extending from at least one edge of the blade portion across a portion of said contact face to hold the counterpart blade and blade portion in said face-to-face contact when interengaged, and limit means upstanding from the opposite lateral edge of said blade portion above the level of said contact face to engage a lateral edge of said counterpart blade to limit relative sidewise displacement of the blade portion and counterpart blade when interengaged while permitting relative longitudinal displacement, a part of the blade portion between said attaching portion and the portion comprising a clip and the limit means being shaped to allow entry of the blade between the clip and limit means and under the clip of a counterpart connector, said blade portion being provided with a slot extending from one edge thereof and passing between the clip and limit means to permit a resilient movement therebetween during the insertion of the counterpart blade.

7. An electrical connector comprising in combination, a pair of duplicate-form terminals each of which has a shank with wire-receiving means, and including a resilient-contact portion capable of being moved to energize said portion with spring tension, a neck formed on each terminal adapting the terminals to be disengageably connected, and limit means disposed opposite each other, at least one of them having a hook-like ear, and with a space left between them on each terminal for receiving the neck of the other terminal, each hook-like ear being spaced from the inside surface of the shank to hold the duplicate-form terminals to each other, said limit means applying pressure to each terminal to spring load both thereof into sustained-pressure contact with each other.

IRVING FREDERICK MATTHYSSE.
